ELECTRONIC HEAT PUMP

Robert L. Carroll, Fairmont, W. Va.

Application July 28, 1954, Serial No. 446,288

7 Claims. (Cl. 62—1)

My invention relates to refrigeration and more particularly to apparatus for refrigeration with an electrical current cycle.

This is a continuation in part of my co-pending application of the same name having Serial No. 326,286, filed December 16, 1952, now abandoned.

In accordance with the prior art of which I am aware, refrigeration has been accomplished by use of a molecular gas cycle in a portion of which a molecular gas is compressed and over another portion of which the molecular gas is allowed to expand. Such a process requires substantial mechanical apparatus for compressing the gas which apparatus is both cumbersome and expensive. Such a process is also impractical at very low temperatures.

Attempts have been made to produce refrigeration by means of electrical cycles but these have met with little success because of losses due to ohmic resistance. However, I have conceived an idea whereby I am able to employ materials with superconductive properties cooled to the point where they are partially or entirely superconductive.

It would seem to the average engineer, skilled in the art, that this would be impractical because tests conducted by some scientists have resulted in the conclusion that the Peltier effect disappears when a conductor becomes superconducting. My calculations show that the reason for this is that with zero resistance all of the current travels in a thin sheath along the outside of the conductor and therefore there was no work function to overcome in their circuit arrangement.

Using super-conductive materials, I employ an electron gas in a manner similar to that in which a molecular gas is employed in the usual refrigeration cycles. The electron gas is compressed and expanded in one embodiment of my invention by changes in work functions between metals and in the preferred embodiment of my invention by changing the size of the conductor.

It is accordingly an object of my invention to provide apparatus for cooling substances substantially below the vaporization temperature of liquid helium.

Another object of my invention is to provide an improved apparatus for refrigeration by purely electrical means.

An ancillary object of my invention is to produce apparatus for employing the Peltier effect for cooling below the superconductive temperature of the materials involved.

Another ancillary object of my invention is to produce electrical apparatus for cooling by expansion and construction of an electron gas.

Still another object of my invention is to provide an improved refrigeration apparatus.

An ancillary object of my invention is to produce a new and novel electrical apparatus.

Still another ancillary object of my invention is to provide means for generating a direct current inside a

2

thermally insulated system while generating a minimum of heat inside said region.

The novel features that I consider characteristic of my invention are set forth with particularity in the appended claims. The invention itself, however, both as to its organization and its method of operation together with additional objects and advantages thereof will best be understood when read in connection with the accompanying drawing, in which:

10 Figure 1 is a showing partially in cross-section and partially in perspective of apparatus embodying my invention wherein a portion of one conductor is located inside the other conductor near the junctions therebetween.

15 Figure 2 is a showing partially in cross-section and partially in perspective of an apparatus in accordance with one embodiment of my invention wherein the smaller conductor is located outside the larger conductor.

20 Figure 3 is a showing in cross-section of an alternative junction between the two conductors which is used in one embodiment of my invention.

25 In accordance with a preferred embodiment of my invention, I provide a first conductor 3 which is shown in the drawing as a wire of small cross-section which is composed of a material which exhibits the property of super-conductivity or zero resistance at very low temperatures. A second conductor 5 also of a superconductive material but of large cross-sectional circumference has one end connected to one end of said first 30 conductor 3 so as to form a "cold" junction 7. The other end of the second conductor 5 is joined to the other end of the first or wire conductor to form a "hot" junction 9.

35 In the preferred embodiment of my invention, the large conductor 5 has a cross-sectional circumference at least ten times the cross-sectional circumference of the small conductor 3. A direct current generator 11 is connected intermediate the ends of the small conductor 3 so as to cause a flow of electrons toward the cold junction 7 through that junction and over the large conductor 5 to the "warm" junction 9.

40 The direct current generator 11 may be either a rotational electric generator as shown in Figure 1, or, in accordance with other embodiments of my invention, other means such as the transformer 13, 15 which is shown in Figure 2, could be employed. The latter system employs a section of wire 3 having connected in series therewith a uni-directional current device 17. An electric field is produced in the transformer secondary 13 in 50 series with the uni-directional device so as to generate an alternating potential in that wire by means of an externally located alternating field producing apparatus such as a helical coil 15.

45 The arrangement of the conductors in my device may be in the form of a normal circuit as in the embodiment shown in Figure 2 or the smaller conductor may be located inside the larger conductor over a portion of its length as in the embodiment shown in Figure 1.

55 In the embodiment shown in Figure 1, the smaller conductor 3 is attached to the large tubular conductor 5 so as to extend coaxially therewith and is located near the cross-sectional center thereof over a portion of its length near the junction between the conductors.

60 In one embodiment of my invention, as illustrated in Figure 1, the material of the inner conductor 3 at each end thereof extends along the inside of the tubular conductor 5 for a substantial distance from the point that it first makes contact with the tubular conductor 5. This extension of the inner wire conductor is formed in the 65 manner of a continuous cylinder separated from the wire except at the end thereof where it makes continuous contact with the wire. A canal 19 is thus formed encircling

the inner wire conductor near the junction. The flared back extension 21 of the inner conductor 3 thus produces a configuration which encourages electrons leaving the inner conductor 3 to pass through both conductors in order to reach the outside of the outer conductor 5. By causing the electrons to pass through the interior of both metals, I thereby cause the production of a Peltier effect in addition to the simple electron gas expansion effect in spite of the superconducting effects.

Surrounding the entire cooling circuit comprising the conductors 3, 5 is a heat insulated outer container 23. Located inside the outer container 23 are two smaller heat insulated chambers 4, 6 one of which surrounds each of the two junctions between the conductors. One of these smaller chambers, which surrounds the "hot" junction, contains a coolant such as liquid helium and the other small chamber, which surrounds the cold junction, contains the material to be cooled.

The operation of this embodiment of my invention is in some respects analogous to that of the ordinary gas refrigeration cycle. In the case of the gas refrigeration cycle compression is produced and circulation is maintained by a mechanical compressor pump. The compressed gas is allowed to expand in the system at the point where cooling is desired. The expansion is a cooling process. For this reason the expanding gas absorbs heat from the immediate surroundings and the surroundings are thereby cooled. The gas then continues carrying the absorbed heat with it until it reaches the region where it is again compressed by action of a pump. In the region of the pump, heat is given up and dissipated by radiation or conduction.

In the operation of a device in accordance with my invention, an electron "gas" is employed instead of a molecular gas. In the metals forming the two half loops of conductor, there is a distribution of free electrons that may be caused to form an electron gas which is free to move in the interstices of the metallic atoms or along the surface of the conductor.

These electrons move through the interior of a metal at room temperatures being distributed rather evenly throughout the conductor due to resistance of the metal. However, at temperatures below a certain level, depending on the material of the conductor, the conductor becomes superconducting. At this point, the conductor has zero resistance. The electrons therefore travel in a sheath around the surface of the metal rather than through the metal.

As the electrons pass from the surface of the small or wire conductor to the surface of the large conductor they spread out and, due to a larger number of free electrons on the surface to constitute the current, they slow down. Thus, we have a situation of a few electrons moving rapidly on the surface of the small wire and a large number of electrons moving slowly on the surface of the large conductor.

In my work in mathematical physics, I have been able to show, contrary to the old electromagnetic theory, that an electron absorbs energy when slowing down and emits energy when increasing velocity. Therefore, as the electrons leave the wire conductor and pass onto the conductor of large circumference, they absorb energy thereby causing a cooling effect in the region of that junction. As the electrons pass from the large conductor to the small conductor they increase in velocity and emit energy into the surrounding medium, thereby producing a heating effect at that junction.

If, therefore, a direct current generator drives a quantity of electrons around the loop, we will have conditions somewhat analogous to expansion of molecular gas although with opposite effect, at that junction where the flow is from the region of greater density to the region of lesser density of the electron gas. This junction is cooled by the process while the other junction is heated. Since at the second junction the electrons are forced

against the junction into a region of increased electron density, the heat may be removed from the system at the "hot" junction by several methods such as by evaporation of liquid helium.

5 In accordance with the preferred embodiment of my invention which is shown in Figure 2, I provide a large cylindrical conductor with a small wire conductor connected internally thereof as shown in Figure 1. In this preferred embodiment of my invention the change in 10 electron velocities is relied on entirely to produce the desired effect without employing the Peltier effect.

In accordance with one embodiment of my invention, I provide a vacuum pump (not shown) for causing the liquid helium to evaporate under reduced pressure thereby 15 increasing its cooling effect in the region of the "hot" junction.

It is well known in the art that at temperatures below 10° absolute, many metals exhibit the property of superconductivity or zero resistance so that the resistance heating is at least negligible if not entirely absent. The metals 20 of which the conductors are constructed should be superconductive at reasonably low temperatures.

Several superconductive elements and alloys as taken from "Phenomena at the Temperature of Liquid Helium" 25 (Burton, Grayson, Smith, Wilhelm), published by Reinhold, 1940, are given below:

Element:	Transition temp., °K.
Mercury	4.12
Tin	3.69
Lead	7.26
Thallium	2.38
Indium	3.37
Tantalum	4.38
Vanadium	4.3
Cadmium	.54
Zirconium	.70
Gallium	1.07
Thorium	1.32
Titanium	1.81
Columbium	9.22
Aluminum	1.14
Zinc	.79
Hafnium	.35
Lanthanum	4.71

5 In accordance with other embodiments of my invention, superconductive alloys may be used in place of superconductive elements. There are a number of such alloys composed of lead, with one other element such as 50 silver, gold, bismuth, copper, mercury, indium or thallium. There are several alloys composed of tin with one of the series, thallium, silver, gold, copper. Also, there are indium-thallium, mercury-cadmium, gold-bismuth, molybdenum-carbon alloys. In general, the superconducting alloy will have at least one superconducting element included. There are other super-conducting alloys, which are compositions of bismuth, tin, lead, or these with cadmium. The combination with arsenic instead of cadmium is an operable alloy also.

60 By employing the term "wire" herein to describe one of the conductors, I do not mean to imply that the conductor must be of circular cross-section. Instead, I mean only that the conductor must be elongated, i. e., that its length be several times as great as its circumference.

65 While in accordance with the preferred embodiment of my invention, it is intended that this apparatus be employed for very low temperatures, it is nevertheless understood that some materials such as galena crystals may be made which have the property of super-conductivity at room temperature.

70 Wherever herein the junctions are described as being insulated from each other it is meant that insulating means are provided for discouraging heat flow from one junction to another. It is understood that no perfect

insulation is obtainable in practice and that some heat will be conveyed along the electrical conductors themselves.

Although I have shown and described specific embodiments of my invention, I am aware that other modifications thereof are possible. My invention, therefore, is not to be restricted except insofar as is necessitated by the prior art and the spirit of the invention.

I claim as my invention:

1. In a device of the class described, a first electrical conductor and a second electrical conductor of superconductive material, said first conductor having a cross-sectional area at least ten times as great as the cross-sectional area of said second conductor, the ends of said first conductor being joined to the corresponding ends of said second conductor, means forming heat insulating chambers surrounding each of the junctions between the first and second conductors, said device forming a heat pump when current is passed through the conductors at superconductive temperatures.

2. In a device according to claim 1, said first and second electrical conductors being hollow.

3. In combination, a first elongated conductor of a first cross-sectional area, a second elongated conductor of a second cross-sectional area having the ends thereof joined to respective ends of said first conductor, one junction being thermally insulated from the other junction, said first and second conductors being composed of members of the group comprising vanadium, zinc and gallium and being superconductive below a predetermined temperature and said first material having a cross-sectional circumference less than one-tenth of the cross-sectional circumference of said second conductor, a chamber provided in the region of one of the junctions for holding a liquified gas in the region of that junction, said gas having a vaporization temperature below the temperature at which said conductors become superconductive, and direct current generating means connected intermediate the ends of one of said conductors in series therewith.

4. In combination, a pair of electrical conductors of material capable of being superconductive, at least one of said conductors being in the form of a hollow shell and having a cross-sectional area at least ten times as great

as the cross-sectional area of said other conductor, the ends of said one conductor being joined to the ends of said other conductor, and direct current generating means connected intermediate the ends of one of said conductors in series therewith.

5. The combination according to claim 4 and further including means forming heat insulating chambers surrounding each of the junctions between the first and second conductors.

6. In a device of the class described, a first electrical conductor and a second electrical conductor of material capable of being superconductive, said first conductor having a cross-sectional area at least ten times as great as the cross-sectional area of said second conductor, the ends of said first conductor being joined to the corresponding ends of said second conductor to form junctions, and direct current generating means connected intermediate the ends of one of said conductors in series therewith whereby when current is passed through the conductors an electron velocity change is effected at said junctions causing an energy radiation at one of said junctions and an energy absorption at the other junction.

7. In combination: a first elongated conductor of a first cross-sectional circumference, a second elongated conductor of a second cross-sectional circumference less than one-tenth of said first cross-sectional circumference, said first and said second conductors comprising materials which are super-conductive below a predetermined temperature, said second conductor being electrically connected to said first conductor on the inside thereof near the ends thereof, said second conductor extending back along the inside of said first conductor, in an encircling manner about said second conductor, for a distance at least three times the thickness of said second conductor, a direct current generator connected in series with said conductors and cooling means in the region of one of the junctions between said conductors.
